UNITED STATES PATENT OFFICE.

WILLIAM J. NESBITT, OF LOS ANGELES, CALIFORNIA.

HEEL-CUTTING APPARATUS.

1,218,303.

Specification of Letters Patent.

Patented Mar. 6, 1917.

Application filed September 16, 1916. Serial No. 120,567.

To all whom it may concern:

Be it known that I, WILLIAM J. NESBITT, a citizen of the United States of America, residing at Los Angeles, county of Los Angeles, State of California, have invented 5 a certain new and useful Heel-Cutting Apparatus; and I do hereby declare the following to be a full, clear, and exact description of the invention, such as will enable others 10 skilled in the art to which it appertains to make and use the same.

This invention relates to heel cutting apparatus, and it has for its main object the provision of a modification and a simplification 15 of the construction which is shown in my application for Patent Serial No. 113,829, filed August 8, 1916.

The present invention will be apparent to those skilled in the art from a careful consideration 20 of the following description of the preferred form of the modified construction, taken in connection with the accompanying drawings in which—

Figure 1 is a broken side elevational view 25 showing the modified construction; Fig. 2 is a plan view of the same; Fig. 3 is a cross-sectional view taken on the line 3—3 of Fig. 1; Fig. 4 is a broken plan view showing the threaded rod connected to the pivot; Fig. 30 5 is a side elevational view of one of the heel holding members; Fig. 6 is an end view 25 of the same; Fig. 7 is an enlarged broken sectional view taken on the line 7—7 of Fig. 5; Fig. 8 is an enlarged broken sectional 35 view of a modified form of the heel holding member; and Fig. 9 is a broken sectional view taken on the line 9—9 of Fig. 3, but showing the threaded rod connected to a yoke on a stationary pivot.

40 Referring to Figs. 1, 2, and 3 of the drawings, the shelf 10 has its rear part secured to the support 11 by screws 12, and on said shelf 10 is movably mounted the platform 13 which has on its underside the 45 dovetail guide 14 which is slidably fitted in a corresponding guideway in the shelf 10.

On the platform 13 is adjustably mounted the table 15 which is preferably recessed 50 on its underside and is provided with a slot 16 through which extends the pivot 17 which latter has its lower part pivotally connected to the platform 13. The table 15 has thereon any suitable form of heel clamping means, that shown consisting of 55 the lower heel holding member 18 which is suitably secured to the side of the table 15,

and the upper heel holding member 19 which is suitably secured to the lever 20; said heel holding members 18 and 19 being provided with projecting portions 21 and 60 with straight toothed or roughened portions 22, Figs. 6 and 7, or curved toothed or roughened portions 22', Fig. 8. The projecting portions 21 are adapted to fit in the crease between the heel seat and the heel of 65 the shoe 23, and the toothed or roughened portions 22 are adapted to grip the heel of the shoe 23. The lever 20 has its forward end provided with the handle 24, and it has its rear end mounted on the pivot 25 between the upright lugs 26 on the rear part 70 of the table 15.

The cutter preferably consists of the bandsaw 27, not fully shown, which may pass through the adjustable guide 28 which 75 is suitably mounted on the shelf 10.

The means for operating the platform 13 preferably consists of the angular lever 29 which is mounted on the pivot 30 carried by the downward extension 31 of the shelf 10; 80 said lever 29 having at one end the handle 32 and having at its other end the pivot 33 to which is connected one end of the curved link 34 which latter has its other end connected to the pivot 35 on the side of the 85 platform 13.

The means for adjusting the table 15 consists of the rod 36 which is rotatably mounted on the table 15 and is adjustably connected to the pivotally mounted pivot 17, Figs. 90 1, 2, and 3, or to the stationary pivot 17', Fig. 9. The stationary pivot 17' is attached to the platform 13 and has pivotally mounted thereon the yoke 37. The rod 36 preferably has one end portion passing through 95 an opening in the lower recessed part of the table 15, and has its other end portion provided with a screw thread 38 whereby it is connected to the pivot 17 or to the cross-piece 39 on the yoke 37. Collars 40 are 100 suitably disposed on the rod 36 in contact with the table 15, and a handwheel 41 or other suitable means is provided on the rod 36 to facilitate turning the latter.

If desired, the slot 16 may be covered by 105 the plate 42 which has an angular portion 43 which is secured to the platform 13 by the screws 44, and which has the flat portion 45 which extends over the upper part of the table 15 and through which the pivot 110 17 or the pivot 17' passes freely.

The table 15 may be locked in adjusted

position on the platform 13 by the clamping nut 46 which is mounted on the threaded upper part of the pivot 17 or the pivot 17' and can be turned by the handle 46' which is connected to it.

From the foregoing description the construction and operation of the modified heel cutting apparatus will be understood by those skilled in the art. It will be seen that 10 when the heel of the shoe 23 is gripped by the heel clamping means on the table 15, the rod 36 may be turned to move the table 15 toward the cutter 27 according to the amount that is to be cut off from the heel. 15 If a straight cut in the heel is to be made the table 15 is disposed substantially at a right angle to the cutter 27 and locked in position by turning the clamping nut 46. By means of the lever 29 the platform 13 20 and the table 15 are moved so that the heel of the shoe 23 is cut by the cutter 27. When it is desired to make an angular cut of the heel the table 15 is turned horizontally on the platform 13 until it makes the desired 25 angle with the cutter 27, whereupon the table 15 may be locked in the adjusted position on the platform 13 by turning the clamping nut 46 on the pivot 17 or the pivot 17'.

I claim:

30 1. In heel cutting apparatus, the combination of a movably mounted platform, a pivot on the platform, a table movably mounted on the platform, shoe-heel clamping means on the table, and means including a 35 rotatable table rod whereby said table is adjustably connected to said pivot.

2. In heel cutting apparatus, the combination of a movably mounted platform, a 40 pivot on the platform, a table resting on the platform and provided with a slot through

which the pivot extends, shoe-heel clamping means on the table, and means including a rod connecting the table adjustably to the pivot.

3. In heel cutting apparatus, the combination of a movably mounted platform, a pivot on the platform, a table resting on the platform and provided with a slot through which the pivot extends, shoe-heel clamping means on the table, a cutter, and means connecting the table to the pivot, so that the table can be moved toward or away from the cutter and also be disposed at the desired angle to the cutter. 45

4. In heel cutting apparatus, the combination of a movably mounted platform, a pivot on the platform, a table movably mounted on the platform, and provided with a slot through which the pivot extends, shoe-heel clamping means on the table, means including a rod whereby the table is adjustably connected to said pivot, and a clamping nut on said pivot for locking the table 50 in adjusted position on said platform. 55

5. In heel cutting apparatus, the combination of a movably mounted platform, a pivot on the platform, a table resting on the platform and provided with a slot through which said pivot extends, shoe-heel clamping means on the table, a rod mounted on 70 the table and having a screw connection with the pivot, and a clamping nut on the pivot for locking the table in adjusted position on the platform. 75

In testimony whereof, I have signed my name to this specification at Los Angeles, county of Los Angeles, State of California, this 6th day of September, A. D. 1916.

WILLIAM J. NESBITT.
